Attorney

UNITED STATES PATENT OFFICE.

WILLIAM A. WILLIAMS, OF BEN WHEELER, TEXAS.

ATTACHMENT FOR ROAD MACHINES.

Application filed October 5, 1927. Serial No. 224,087.

My invention relates to road making machines, and particularly to a Bermuda grass cutting attachment therefor.

The primary object of my invention is to provide a Bermuda grass cutting or destroying attachment so constructed that it may be readily applied to the rotarily adjustable ring or annulus from which the scraper blade of an ordinary road grader or scraper is supported.

A further object is to provide an attachment of this character which is extremely simple and durable in construction and efficient in operation.

15 The invention consists in the novel form, combination and arrangement of parts hereinafter more fully described, shown in the accompanying drawings and claimed.

In the drawings:

20 Figure 1 is a side elevation of a road machine equipped with my grass and weed cutting and destroying attachment.

Figure 2 is a top plan view thereof.

25 Figure 3 is an enlarged front elevational view of the attachment applied to the annulus of the road machine, the annulus being in section, and

Figure 4 is a perspective view of the supporting bar of the attachment.

30 My invention is adapted to be applied to any ordinary road grader or scraper, and the one shown has a supporting frame composed of side bars 5 which diverge rearwardly and are supported by front wheels 6 and rear wheels 7.

35 Mounted on the under sides of the bars 5 is an annulus 8 which may be rotarily adjusted relative to the axis of the scraper. A vertically concave scraping blade is usually mounted below and carried by the annulus 8 by the use of suitable brackets or the like, as is well known in the art.

40 My invention consists in the provision of a grass and weed cutting and destroying device adapted to be attached to the annulus 8 in place of the scraper blade so that the latter and my device may be interchanged whenever desired or necessary. My attachment consists of a supporting bar 9 adapted to extend across and to be secured to the under side of the annulus 8 in contact with opposite lower edge portions of the latter, and having a plurality of depending standards 10 secured thereto at regular intervals, the lower ends 50 of these standards having alined bearings 11 in which is journaled a horizontal shaft 12

carrying cutting disks 13 that are arranged in uniformly spaced relation.

As shown, the supporting bar 9 is formed with elongated slots 14 in the ends thereof through which extend bolts 15 by means of which angle brackets 16 are secured to the supporting bar for adjustment toward or away from each other. The angle brackets 16 are adjusted against opposite sides of the annulus 8 and then bolted to the latter, as at 17, so that the attachment is rigidly secured to the annulus.

The openings 18 in bar 9 permit bolting of the standards 10 thereto, as at 19.

45 As the bars 5 are usually adjustable vertically, the disks may be lowered into contact with the ground and upon forward travel of the machine, the disks will roll thereon and the cutting edges thereof will effectively cut and destroy Bermuda grass, weeds and the like. By adjusting the annulus, the axis of the disks may be disposed at the desired oblique angle to the machine axis or line of travel for insuring effective cutting of the grass and weeds for the entire width of the attachment. Upon raising the bars 5, the discs may be lifted clear of the ground, and upon removing the bolts 17, the attachment may be readily removed and the usual scraper 50 blade applied.

The draft strains are taken off of the standards 10 by providing draft bars 20 which are rigid with certain of the bearings 11 and extend forwardly and upwardly therefrom in converging relation and are bolted to the inner side of the forward part of the annulus 8 in front of bar 9, as at 21.

55 Minor changes may be made without departing from the spirit and scope of the invention as claimed.

What I claim as new is:

1. The combination with the frame of a road making machine, an annulus supported on the frame, of a Bermuda grass cutting attachment comprising a supporting bar extending transversely of the line of draft, means detachably securing the supporting bar to the under side of said annulus, cutter disks having coincident axes extending parallel with said supporting bar and means for hanging the cutter disks from said supporting bar, said securing means embodying angle brackets adjustably secured to the ends of the supporting bar for movement toward or away from each other.

2. The combination with the frame of a

road making machine, an annulus supported on the frame, of a Bermuda grass cutting attachment comprising a supporting bar extending transversely of the line of draft, 5 means detachably securing the supporting bar to the under side of said annulus, cutter disks having coincident axes extending

parallel with said supporting bar and means for hanging the cutter disks from said supporting bar, and draft bars extending forwardly from the disk hanging means and removably attached to the front of the annulus. 10

In testimony whereof I affix my signature.

WILLIAM A. WILLIAMS.
